UNITED STATES PATENT OFFICE.

WILLIAM JOSEPH RILEY, OF BIRMINGHAM, ENGLAND.

BANJO.

SPECIFICATION forming part of Letters Patent No. 636,179, dated October 31, 1899.

Application filed June 6, 1898. Serial No. 682,712. (No model.)

To all whom it may concern:

Be it known that I, WILLIAM JOSEPH RILEY, musical-instrument manufacturer, a subject of the Queen of Great Britain, residing at 25 5 Constitution Hill, in the city of Birmingham, England, have invented certain new and useful Improvements in Banjos, of which the following is a specification.

This invention has for its object to provide 10 a new and improved construction of banjo, and this object is accomplished in the manner and by the means hereinafter described and claimed, reference being made to the accompanying drawings, in which—

15 Figure 1 is a longitudinal central sectional view taken on the line $x-x$, Fig. 3, showing a banjo embodying my invention. Fig. 2 is a broken side elevation of the same. Fig. 3 is a front plan view of the same. Fig. 4 is a 20 detail sectional view taken on the line $x'-x'$, Fig. 3; and Fig. 5 is a detail end elevation, the tailpiece being broken away to show the engagement of the looped tail ends of the strings with the pegs or pins.

25 The same letters of reference indicate corresponding parts in the several figures of the drawings.

In constructing a banjo according to the said invention the body is composed of a hoop 30 or ring a , made in a single piece of metal and formed integral, with an annular stiffening and reinforcing flange or rib a' projecting inwardly from its inside at a point rather above the middle line of the hoop, the outer periphery 35 of which is made of two diameters, a^2 being the upper and small part, while a^3 is the larger and lower portion, with the annular step a^4 between them coming at a point about opposite to the inside flange or rib a' . En- 40 circling the upper end of the hoop is a vellum-stretcher ring or bezel b , by which the vellum-head c of the instrument is held in place and tensioned by its under edge b' impinging against the vellum-wire d , which is in the 45 form of a ring encircling the top of the hoop and around which the edges of the vellum are passed and then come between the bezel and the outer surface of the hoop, as usual. The drawing down of the ring b for tensioning or 50 tightening up the vellum is effected by means of a series of screws e , passing vertically downward through plain holes b^10 in the

said ring and with their heads e' lying flush with sinkings b^2 , surrounding the upper ends of the said holes b^10 , while the screw tail ends 55 e^2 take into inside screwed bushes f , preferably made of gun-metal and secured, so as to be incapable of rotation, within the upper parts g' of holes g , made around the shelf or step part a^4 of the hoop, while the continuations g^2 of the said holes are plain and receive and conceal the said tail ends of the screws.

The neck h of the instrument, which has the finger-board h^2 upon the top side, is dow- 65 elled at h^3 and takes into a socket or foot i , made of aluminium or other metal, which is attached to the hoop either by screws i' , as represented, or in any other convenient way.

The strings j pass over an ordinary bridge 70 j' and underneath a bar j^2 , directed across the vellum and having its opposite ends j^3 adjustably connected, as hereinafter described, to the tensioning-ring b of the instrument, and thence to the tailpiece k , consisting of a 75 series of small pins or pegs k' , directed downwardly from a beading k^2 on the said ring b and adapted to receive the looped ends j^4 of the strings.

The tailpiece k comprises a plate of metal 80 soldered or otherwise secured to the ring b and having an overlying corrugated cover part j^5 , whereby the tail ends of the strings and the pegs or pins k' are concealed. In Fig. 5 the central part of the tailpiece is omitted 85 to show the pegs or pins and the looped tail ends of the strings engaged therewith. I may, however, employ any suitable construction of tailpiece, and therefore do not confine myself to the one shown and described. 90

The attachment and adjustment of the end plates j^3 of the cross-bar j^2 , under which the strings pass and thereby keep the bridge pressed down upon the vellum, are effected at each end by a series of three screws, the middle one, j^4 , of which passes through a middle hole in the end plate j^3 , with its head j^6 bearing on the top of the said plate and its tail end taking into a screwed hole j^7 , made to receive it in the ring b , while other adjusting-screws j^8 j^9 100 come one on either side of the middle screw, with their heads coming on the under side of the said plate j^3 , and thus form stops, against which the said plate bears when forced down

by the screwing home of the screw j^4 . When the bar requires to be raised, the middle screw of each end plate is slackened back to the required extent, the ends following it up by the lifting force exerted by the strings against the under side of the bar, and then the side screws j^8 j^9 are raised by a screw-driver inserted through the holes j^{10} until their heads abut against the under sides of the end plates, after which the whole is made rigid by tightening up the center screws j^4 .

The rotation of the screws for adjusting the vellum-ring is effected by a screw-driver, and instead of the holes in the step-flange of the hoop being provided with gun-metal bushes such bushes may be dispensed with and the holes themselves may be wormed to receive the tail ends of the adjusting-screws.

The tension cross-bar j^2 causes the strings to assume a sharp angle near the bridge j' , and thereby exert considerable down pressure or pull on the bridge, which effectually prevents it from chattering, thus materially improving the tone of the instrument.

Having fully described my invention, what I desire to claim and secure by Letters Patent is—

1. A banjo having its body composed of a metal hoop or ring formed integral on its inside with an inwardly-projecting, annular, stiffening-rib, and its exterior constructed of two different diameters respectively above and below said rib and separated at their exterior by a flattened, annular step, substantially as described.

2. A banjo having its body composed of a hoop or ring made of a single piece of metal

formed integral on its inside with an inwardly-projecting solid stiffening-rib and its exterior constructed of two different diameters respectively above and below said rib and separated at their exteriors by an annular step containing a series of screw-threaded sockets, substantially as described.

3. A banjo, consisting of a hoop or ring made of a single piece of metal formed integral with an internal solid stiffening-rib and constructed exteriorly of two different diameters respectively above and below said rib and separated at their exteriors by an annular step containing a series of screw-threaded sockets, a vellum, a vellum-stretching ring encircling the part of the hoop or ring of least diameter, and adjusting-screws engaging the vellum-stretching ring and screwed into the screw-threaded sockets within said annular step, substantially as described.

4. The combination with the strings, the vellum, the vellum-stretching ring, and the bridge-piece of a banjo, of a tension-bar crossing the strings near the bridge-piece and having end plates, screws passing through said end plates into the vellum-stretching ring, and stop-screws adjustable in said ring and having their heads bearing against the under sides of said end plates, substantially as described.

In testimony whereof I have hereunto set my hand in presence of two subscribing witnesses.

WILLIAM JOSEPH RILEY.
